SOUND TRANSMITTING APPARATUS

Günther Wurdel, Berlin, Germany, assignor to
 Apparatebau Gesellschaft Neumann & Borm
 Kommanditgesellschaft, Berlin, Germany

Application June 12, 1935, Serial No. 26,271
 In Germany August 25, 1934

10 Claims. (Cl. 179—103)

This invention relates to a sound-transmitting apparatus for telephone systems.

The primary object of the invention is to provide a telephone for use under conditions whereby a telephone of the ordinary kind will not give satisfactory results owing to interfering noises, as for instance in the engine rooms of ships, in aircraft, or in numerous other instances in which prevailing noises will completely drown the voice of the person speaking.

A further object of the invention is to provide a microphone free from chattering effect and having a practically straight characteristic which is devoid of resonance in the audible range.

15 By chattering effect is meant the reverberatory effect or non-linear distortion which arises in the case of ordinary telephone microphones due to the fact that, owing to the mechanical nature and disposal of the diaphragm, the movement of the 20 diaphragm is not equal on both sides.

A still further object is to provide a telephone in which the effective surface of the microphone, when the telephone is in use, is situated in a plane passing through the corner of the mouth of the speaker.

25 A further object is to make provision for excitation of the effective surface of the microphone in immediate fashion by the spoken words.

These and other objects and advantages of the invention will become apparent as the description 30 proceeds.

It has already been proposed to employ in rooms in which there is a considerable volume of noise laryngeal microphones, which receive the speech vibrations by being placed against the larynx or the lower jaw of the speaker. Even with microphones of this kind, however, it is merely possible to a limited extent to preclude the effect of interfering noises. The articulation is 35 also unsatisfactory, because the higher speech oscillations, which are particularly important for proper intelligibility, are, despite the location of the microphone against the larynx or the jaw, absorbed by the intermediately disposed skin, 40 which acts as a cushion, and in consequence do not wholly reach the microphone. Moreover in numerous spoken sounds there is no appreciable vibration on the part of the jaw or the larynx.

45 Any attempt to overcome the strong drop in the alternating potentials delivered by the laryngeal microphone in the range of the higher speech oscillations by the inclusion of rectifying elements between the microphone and the sound reproducing means does also not lead to the desired result, as the drop in the direction towards the higher speech oscillations does not take place evenly, i. e., in a straight line, but is disturbed by the fact that in the case of numerous spoken sounds, particularly sibilant sounds, there is no conduction of the sound on the part of the body.

whilst in other sounds an exaggerated emphasis on the initial part of the sound causes a complete distortion of the tone.

To avoid the disadvantages associated with laryngeal microphones attempts have been made to employ microphones which are excited by sound in the air, and in which there are provided special auxiliary means, for example screening or damping means, which have the object of withholding interfering noises from the microphone. Screening and damping means of this kind certainly cause a decrease of the interfering noises at the effective microphone surface, but at the same time they also nullify a part of the voice energy to a similar extent. Moreover when using 15 the microphones hitherto usual for telephonic purposes it is impossible to hold the same as close to the mouth as would be desirable, as owing to the greatly increased voice energy impinging on the surface of the microphone the distortion of 20 the speech would in this case be so considerable as to render intelligibility impossible. These 25 distortions are caused by the fact that the microphones, when a certain volume of sound is exceeded, are overmodulated. A distortion of the speech also occurs when the microphone is approached too closely towards the mouth because in the case of the carbon microphones hitherto used for telephonic purposes the particles of carbon do not, as a result of the very high exciting 30 intensity, oscillate properly about a fixed position of equilibrium, but are thrown out of their original position and do not again return to the same. There then occurs what I have termed a chattering 35 effect.

Assuming an attempt is made so to construct the damping means above referred to that the overmodulation or the chattering effect of the microphone is eliminated, this will also not lead to the desired result, as the frequency characteristic of the microphone is not disposed in a straight line but possesses powerful resonance points at numerous points of the audible range. Generally speaking, interfering noises are not confined to a narrow section of the entire sound 40 range. Accordingly, at resonance points of the microphone affected by corresponding interfering frequencies, the alternating potentials delivered by the microphone increase to such extent that the interfering noise occurs in a much more powerful form at the reproducing apparatus than is represented by the ratio between interfering noise and voice energy at the microphone. It is, therefore, impossible to obtain a proper reproduction of speech in noisy rooms with the microphones of poor frequency characteristic heretofore employed for telephonic purposes.

50 Microphones are known, which possess a good frequency characteristic, that is to say—which do not reveal any or any appreciable resonance 55 60

points within the entire audible range. These microphones accordingly reproduce the voice energy passed to the same without any appreciable distortion. Their frequency characteristic, therefore, is disposed practically in a straight line, i. e., is devoid of resonance points. These microphones, which may be constructed as contact or also condenser or electro-dynamic sound transmitters have heretofore been employed for radio transmitters, the making of talking machine records and for sound-film purposes, as in these cases it is necessary to attain a very natural reproduction of speech and music, which would be impossible with the carbon microphones employed in the telephonic art. Microphones having a good frequency characteristic have heretofore not been employed at all for telephonic purposes, primarily on account of their small sensitivity, which renders necessary an amplification of the alternating potentials supplied by them. It is quite readily possible, without detriment to the good properties of the same, to construct these microphones in a small size suitable for the purposes of the present invention. Of the microphones of good frequency characteristic above referred to the contact transmitter possesses a comparatively good sensitivity.

Now it has been ascertained that microphones of good frequency characteristic also have no chattering effect even if—in departure from the mode of use hitherto usual—the effective surface of the microphone is approached as close as possible towards the mouth, where the sound output of the speech possesses its maximum value. This necessitates that the microphone, also in contradistinction to the sound transmitters previously employed for telephonic purposes, does not have a mouthpiece or the like. Heretofore it has been the general impression that a mouthpiece of the elongated or trumpet variety could not be dispensed with as this served to withhold at least in part the interfering noises and to exert a favorable effect on the frequency characteristic of the microphone. If, however, in the case of the microphone of straight frequency characteristic employed according to the invention a trumpet or similar mouthpiece were employed, the column of air enclosed within the mouthpiece and acting as resonator would also be caused to oscillate by some frequency of the interfering noise. The interfering noise audible in the receiver would accordingly assume a different character in tone, and would be much stronger than would correspond with the intensity of the sound at the sound inlet aperture. It is known in itself in the acoustical art that the sound output increases approximately according to a quadratic function with approach towards the sound source. It has, however, not been appreciated heretofore that the sound output assumes in the immediate vicinity of the mouth, i. e., at the point of the sound generation, enormous values which are incapable of being measured even with the apparatus available at the present time.

The invention will be described more fully with reference to the accompanying drawing, in which

70 Fig. 1 is a diagram showing the alternating potential delivered by a microphone dependent on the distance of the latter from the source of sound.

Fig. 2 is a perspective view showing the telephone according to the invention in actual use.

Figs. 3 and 4 are front and side views of the form of embodiment of the telephone according to Fig. 2, Fig. 4 being partly in section.

Figs. 5 and 6 are front and side views of a modified form of embodiment of the telephone.

In the diagram according to Fig. 1 the curve *a*—*b* shows in millivolts the alternating potential delivered by a microphone approached more and more towards the source of sound, i. e., dependent on the distance, measured in millimetres, of a source of sound with constant sound energy from the microphone. The broken line *c*—*d* indicates the intensity of an interfering noise in the same room, this intensity remaining the same at the point of the effective surface 15 of the microphone.

It is shown by this diagram that the sound energy in the range of the usual spacing of the effective surface of the microphone from the source of sound, i. e., in the range of approximately 40 to 70 mm., is completely covered by the interfering energy (*c*—*d*). If the source of sound is greatly approached towards the microphone, i. e., to within approximately 6 mm., the alternating potential delivered by the microphone increases in the case of the example shown in the diagram to more than ten times the value of the interfering potential. The steep ascent of the curve *a*—*b* in the case of small spacial disposal provides a certain indication of the unusual extent to which the potential delivered by the microphone will rise when the microphone is approached even more towards the sound source, i. e., is moved immediately up to the latter.

It will accordingly be obvious from the above that the approach of the effective surface of the microphone of good, i. e., straight frequency characteristic employed according to the invention immediately up to the mouth of the person speaking is of decisive importance. Since the ratio between voice energy and interfering energy at the effective surface of a microphone situated immediately against the source of sound is exceptionally favorable, particular precautions do not require to be taken to withhold the interfering noise from the microphone. Practical experiments have shown that with the apparatus according to the invention proper and faultless intelligibility is capable of being obtained even if the unprotected ear is acted upon even to the extent of a sensation of pain.

It has also been found that particular advantage is obtained if the current of air produced upon speaking is not allowed to impinge vertically on the surface of the microphone situated immediately in front of the mouth and thus exert a detrimental effect on the vibrations. According to the invention, therefore, the effective surface of the microphone arranged in the immediate vicinity of the source of sound is disposed approximately parallel to the direction of speech, i. e., to the direction of movement of the current of air formed upon speaking. With this arrangement the current of air is more or less able to sweep past the surface of the microphone, so that it is then unable appreciably to distort the alternating potentials delivered by the microphone. Preferably the holding member for the microphone is so constructed that the effective surface of the microphone when the receiver is placed against the ear is situated at the corner of the mouth.

As shown, for example, by Fig. 2, the effective microphone surface 2, which is located in a protective casing 1, is situated, when the holding

member 3 with the receiver 4 is lifted to the ear, very close to the corner of the mouth of the speaker. The microphone, therefore, as shown in Fig. 4, is not furnished with the usual trumpet-like or similarly shaped mouthpiece. As stated above, there is employed a microphone with good, i. e., approximately straight frequency characteristic not revealing a chattering effect.

In the forms of embodiment shown in the drawing the holding member 3 has affixed thereto both the transmitter 1, 2 as well as the receiver 4. Naturally, as regards the invention, it is quite immaterial whether the microphone and the receiver are united in one holder, or whether the holder, which may be placed for example about the head, carries merely the transmitter 1, 2. The essential feature is that the surface of the microphone 2 is situated in the immediate vicinity of the source of sound.

20 To be able to adapt the requisite small spacing of the effective microphone surface according to the invention to different sizes of head the transmitter is secured to the holding member 3 so as to be adjustable in the plane of the microphone surface 2.

In the form of embodiment according to Figs. 2 to 4 this adjustability is obtained by an arm 5, which is eccentric and mounted to be rotatable in a corresponding abutment 6 on the holding member. In this way it is a simple matter to adjust the transmitter in such fashion in relation to the holding member in the plane of the microphone surface as to ensure the necessary minimum spacing of the microphone surface from the source of sound.

In the form of embodiment according to Figs. 5 and 6 the casing 1 of the transmitter is mounted to be oscillatory on the holding member 3 by means of an arm 7.

40 It will be understood that the invention is not limited to the specific details of construction illustrated in the drawing, and that numerous modifications are quite possible within the meaning of the above description and the annexed claims without departing from the spirit of the invention.

What I claim as new and desire to secure by Letters Patent is:

1. A telephone transmitting and receiving set comprising a rigid holder, a receiver mounted at one end thereof and an abutment carried by the other end of said holder, a microphone casing having an arm eccentrically fixed thereto, said arm being rotatable on said abutment, and 55 a microphone of relatively low sensitivity mounted in said casing.

2. The device as claimed in claim 1, in which the plane of the effective surface of the microphone is always parallel to the effective surface of the receiver.

60 3. The device as claimed in claim 1, wherein the microphone casing arm extends angularly from the casing.

4. A telephone transmitting and receiving set 65 comprising a holder, a sound receiving apparatus mounted in said holder, a microphone free of chattering effect and having a practically straight frequency characteristic which is devoid of resonance in the audible range, adjustably mounted at the other end of the holder, the construction and arrangement being such that when the sound receiving apparatus is held to the ear the effective surface of the microphone may lie

at the corner of the mouth of the user and in a plane parallel to the breath currents of the user.

5. In a telephone transmitting and receiving set, a non-mouthpiece microphone casing and a microphone free of chattering effect and having a practically straight-line frequency characteristic in the audible range, the said microphone being mounted forwardly in the said casing, and the construction and arrangement being such that the effective surface of the microphone is 10 movably disposed in the immediate vicinity of the speaker's mouth to positions substantially parallel to the direction of speech when the telephone is in use.

15 6. In a telephone transmitting and receiving set, a non-mouthpiece microphone casing, a microphone free of chattering effect and having a practically straight-line frequency characteristic in the audible range, the said microphone being mounted with its effective surface forwardly in 20 the said casing substantially parallel to the direction of speech when the telephone is in use, and means for moving the effective surface of the said microphone while maintaining the effective surface thereof in the same plane to a position in the 25 immediate vicinity of the speaker's mouth irrespective of the size of the head of the speaker.

7. A sound transmitting device for telephone systems intended for use more particularly under noisy conditions, comprising a microphone, free 30 from chattering effect and having a practically straight frequency characteristic, devoid of resonance in the audible range, said microphone being adjustably mounted in a telephone set, so that when the receiver is applied to the ear, the 35 effective surface of the said microphone may be moved in a plane of the surface thereof so as to be situated in the immediate vicinity of the speaker's mouth at one of the corners thereof.

8. A sound-transmitting device according to 40 claim 7, in which the effective microphone surface arranged in the immediate vicinity of the source of speech is located in a plane, which is directed parallel or approximately parallel to 45 the direction of movement of the current of air resulting upon the formation of the spoken sounds.

9. A receiving and transmitting set for telephones, intended for use more particularly under 50 noisy conditions, comprising a stock, a receiver mounted therein, an arm mounted in said stock, a microphone free from chattering effect and having a practically straight frequency characteristic, devoid of resonance in the audible range, mounted in said arm the axis of said microphone 55 being eccentric to the arm's axis of rotation and the plane of the surface of said microphone parallel to the face of the said receiver.

10. A telephone transmitting and receiving set, comprising a holder, a sound receiving apparatus 60 mounted in said holder, a non-mouthpiece microphone casing mounted on the holder, a microphone free of chattering effect and having a practically straight frequency characteristic which is devoid of resonance in the audible range mounted 65 forwardly in the said casing, the construction and arrangement being such that when the sound receiving apparatus is held to the ear the effective surface of the microphone may be moved to lie at the corner of the mouth of the user and in a 70 plane parallel to the breath currents of the user.
